UNITED STATES PATENT OFFICE.

CHARLES L. MICHOD, OF CHICAGO, ILLINOIS.

FENCE.

1,175,468.

Specification of Letters Patent. Patented Mar. 14, 1916.

Application filed January 27, 1915. Serial No. 4,696.

To all whom it may concern:

Be it known that I, CHARLES L. MICHOD, a citizen of the United States, residing at 538 South Clark Street, Chicago, in the county of Cook and State of Illinois, have invented a new and useful Improvement in Fences, of which the following is a specification.

One feature of my invention relates to fences employing line-posts of metal of angle-shape in cross-section formed of flexible material, as for example, vanadium, or high carbon, steel, with anchorages on their lower, embedded, ends which are planted below the level of the ground so that resilient portions of the posts are embedded in the ground, whereby the line-posts are rendered flexible, and by reason of the embedding in the ground of resilient portions of the posts, the embedding earth operates to cause an action in the nature of a feather-spring action to occur, which reduces very materially the shearing stresses on the posts. The fencing is secured against the faces of these posts in accordance with common practice, and it has been found that when the face against which the fencing extends is flat, the wires are not held to the posts with sufficient rigidity to prevent the fence-wires from slipping relative to the posts when the fencing and posts are strained laterally as by an animal running or lying against the fence. Thus, should lateral strains be exerted against a portion of the fencing, the twisting of the adjacent post is not resisted by the other wires of the fencing attached to this post to the same extent that it would be resisted were the wires held to the posts against slipping, and as a consequence, the posts must be made relatively heavy to resist such twisting action which, if permitted to take place beyond a certain degree, subjects the posts to the danger of buckling under lateral strains. The making of the posts heavy, as stated, requires that the width of the flange of the post against which the fencing is secured and which flatwise opposes the ground in flexing, as posts have heretofore been constructed, be such that the feather-spring action stated is not capable of being effected to the most desirable degree. Furthermore, as will be understood, the wider the flange which flatwise opposes the ground in the flexing of the post, the

greater the twisting strain on the post as 55 the portion of the strain taken by the post in flexing is correspondingly reduced, and thus the more metal required to prevent twisting of the post.

One of my objects is to provide a construction of fencing to the end that the line-posts thereof may be provided of the desired narrowness of face opposing the ground in the flexing operation for producing the most efficient feather-spring action, and that 60 twisting of the line-posts be reduced to the minimum, thereby minimizing the cost of 65 the fence-post and causing the fencing to operate with the highest efficiency.

Another object is to provide a highly economical form of post, either flexible or rigid, and of angle-shape in cross-section, which may be used with the common form of relatively short staples for attachment of the fencing thereto, and which shall serve to 70 hold the fencing thereto without danger of 75 breaking or becoming otherwise injured.

Referring to the accompanying drawing: Figure 1 is a view in elevation of a fence constructed in accordance with my invention and showing the wire-fencing in the form of a webbing. Fig. 2 is an enlarged view showing one of the line-posts of the fence and one of the horizontal wires of the webbing. Fig. 3 is a section taken on the line 3 on Fig. 2 and viewed in the direction of the arrow. Fig. 4 is a section taken at the line 4 on Fig. 3 and viewed in the direction of the arrow. Fig. 5 is a view similar to Fig. 4 of another form of line post. Fig. 6 is a view similar to Fig. 2 of still another form of line-post. Fig. 7 is a section taken at the line 7 on Fig. 6 and viewed in the direction of the arrow; and Fig. 8, a section similar to Fig. 7 of still another form of 80 post.

In the construction shown in Fig. 1, a suitably braced rigid end-post is shown at 8, line-posts at 9, and fencing, in the form of webbing, at 10, formed of longitudinally 85 extending horizontal wires 11 and transverse vertical wires 12, preferably intermeshed, or otherwise engaged with, the wires 11 in any 90 suitable manner, as in general practice. The line-posts 9 are provided, in practice, with 95 enlarged anchorages 9^a of any suitable construction, which are preferably embedded in the ground below the level thereof, and in

accordance with one of the features of my invention, must be embedded in the ground with the portions of these posts between the level of the ground and the tops of the anchorages embedded in the ground.

In Figs. 2, 3 and 4, one of the similar line-posts is represented, the cross-sectional view (Fig. 4) illustrating the shape of the side of the line-post against which the wire-fencing is secured, this side of the post being concave, as represented at 13, to present a pair of spaced bearing surfaces, or points, 14 and 15, for engagement with the longitudinal wires 11 which are firmly held against the surfaces 14 and 15 by any suitable means, as for example, staples 16, which embrace the horizontal wires 11 and pass through openings 17 in the post, at the rear side of which the ends of the staples are spread apart, as shown (Fig. 3), to firmly hold the fencing in position. In applying the staples 16, as stated, the wires 11 are deflected slightly inward, thus drawing them taut and gripping them firmly against the surfaces 14 and 15, which latter, together with the staples 16, afford three-point contacts with the wires and thus serve to very firmly secure the fence-wires to the posts.

In Fig. 5 is shown another form of line-post, wherein the principle of the post shown in Figs. 2, 3 and 4 is carried out. In this construction, the post, instead of being L-shape in cross-section, is of general T-shape, the face of the post against which the wires 11 bear being concaved, as represented at 18, to provide spaced points 19 and 20, into firm contact with which the longitudinally extending wires of the fencing are drawn, upon applying to position a staple 21, which embraces the wire 11 between the bearing surfaces 19 and 20, and extends at its ends through openings 22 in the post, and has its ends deflected against the rear side of the portion of the post in which the concave surface is provided.

It will be noted that in each of the forms of line-post described, the side of the post against which the wires 11 extend, is reinforced by the rearwardly extending flange of the post, indicated at 23 in Fig. 4, and 24 in Fig. 5. This feature of the construction presents advantages whether the posts are rigid or flexible, as stated above.

It is manifest that a line-post must be so constructed that it will present the requisite strength for resisting the strains to which it is subjected in use, and that if the ordinary form of staple, which is relatively short, is to be used, the recess between the spaced bearing points on the post against which the wire bears, must be relatively shallow. By constructing the post with a flange, such as the flange 23 or 24, which extends laterally of the fencing, the post is so reinforced

that the portion of the latter which extends at an angle to the said laterally extending flange, and against which the fencing bears, may be constructed with a relatively shallow recess to afford the spaced bearing-surfaces for the wires 11, whereas were these laterally-extending flanges not provided, the post, in order to afford the relatively shallow recess for permitting ordinary staples to be used as the fencing-fastening means, would be required to be so bulky in order to present the desired strength, that they would be uncommercial.

When the feature just described is incorporated in a flexible post, where the anchorages thereof are located below the level of the ground and resilient portions of the post are likewise embedded in the ground, a very decided advantage is afforded over line-posts provided with flat faces against which the fencing bears, due to the fact that by the engagement of the wires 11 with spaced bearing surfaces on the post with the fastening device engaging the wires intermediate these bearing surfaces, the wires 11 are firmly held to the post and in such manner that when the fencing is subjected to lateral strains, slipping of the wires and posts relative to each other will not occur, and thus when forces are exerted laterally against the fencing, resistance to twisting of the posts is aided by the other wires of the fencing. Furthermore, the surface of the post which opposes the ground in the flexing operation may be made sufficiently narrow, as compared with the width of the re-inforcing flange of the post which extends laterally of the fencing, to cause the desired resistance to be offered by the ground to the post for producing the most efficient feather-spring action. It will also be manifest that by the combination of these features, the line-post may be made relatively light in weight as no necessity exists for providing in the post to resist torsional strains, metal in addition to that required for rendering the posts sufficiently strong to resist lateral forces.

The constructions shown in Figs. 6, 7 and 8 present examples of another way in which the wires 11 may be so associated with the line-posts of the resilient type above referred to, as to firmly secure these wires to the line-posts, and afford the advantages hereinbefore set forth.

Referring particularly to Figs. 6 and 7, the line-post therein illustrated is of general L-shape in cross-section, with the side thereof against which the longitudinal fence wires 11 extend, of convex form, as represented at 25. The wires 11 may be secured against this convex face by any suitable fastening means, those illustrated comprising a wire 26 which extends between its ends around the rear side of the post and inter-

locks at its ends with the wire 11 at opposite edges of the convex surface 25, as indicated at 27, the wire 26 being drawn sufficiently taut to cause the wire 11 to lie 5 against the surface 25 more or less conformingly and cause such an association of the wire 11 with the post that there can be no relative slipping between the post and fencing.

10 The principle underlying the construction illustrated in Fig. 7 is also embodied in the construction illustrated in Fig. 8, wherein the post, instead of being of L-shape in cross-section is of general T-shape, with the 15 side thereof against which the fencing wires 11 extend, convexed, as indicated at 28, and coöperating with the wires 11 as explained of the convex surface 25 in Fig. 7.

The provision of the posts as shown in 20 Figs. 7 and 8 causes the fencing to be so related thereto when secured to the posts, as illustrated, as to permit posts with relatively narrow faces, against which the wire-fencing is secured, to be provided, and the fencing-wires 11 to be secured to the posts against slipping; and, in fact, may be made 25 of such narrow width relative to the portion of the post which extends laterally of the fencing, that the resistance offered by the 30 ground to the flat-wised disposed side of the post in the flexing operation, will be that required for the most efficient feather-spring action.

What I claim as new and desire to secure by Letters Patent is:—

35

1. In a fence, the combination of a resilient line-post having its lower resilient portion embedded in the ground, said post being formed of longitudinally extending members disposed at an angle to each other, 40 fencing extending across the line-post, and fence securing means on one face of the post adapted to hold the fencing at different vertical elevations against slipping thereon under torsional strains on the post, said fencing extending at an angle to the other face of the post, the face against which said fencing bears being of less width than the other face disposed angularly thereto.

45

2. In a fence, the combination of a resilient line-post of substantially L-shape in cross-section having its lower resilient portion embedded in the ground, the face of one of the flanges of the post being offset to provide spaced bearing surfaces, fencing extending across said bearing surfaces, and means on the post engaging the fencing at different vertical elevations for holding the fencing firmly against said bearing surfaces, 55 the flange affording said bearing surfaces being of less width than the other flange of the post.
